DESIGN FOR A FACE POWDER CONTAINER

Raoul E. Hankar, Scarsdale, N. Y., assignor to L. T. Piver, Inc., Wilmington, Del., a corporation of Delaware

Application April 12, 1935, Serial No. 56,343

Term of patent 14 years

To all whom it may concern:

Be it known that I, Raoul E. Hankar, a citizen of the United States, residing in Scarsdale, county of Westchester, and State of New York, have invented a new, original, and ornamental Design for Face Powder Container, of which the following is a specification, reference being had to the accompanying drawing, forming a part thereof.

In the drawing:

Fig. 1 is a top view of a face powder container
showing my new design.

Fig. 2 is a side view thereof.

I claim:

The ornamental design for a face powder container substantially as shown.

RAOUL E. HANKAR.
